C. A. CARSCADIN & G. A. WOODMAN.

YOKE FOR DRAFT GEAR.

APPLICATION FILED MAY 28, 1913.

1,076,866.

Patented Oct. 28, 1913.

UNITED STATES PATENT OFFICE.

CHARLES A. CARSCADIN AND GEORGE A. WOODMAN, OF CHICAGO, ILLINOIS.

YOKE FOR DRAFT-GEAR.

1,076,866.

Specification of Letters Patent.

Patented Oct. 28, 1913.

Application filed May 28, 1913. Serial No. 770,297.

To all whom it may concern:

Be it known that we, CHARLES A. CARSCADIN and GEORGE A. WOODMAN, citizens of the United States, both residing at Chicago, in the county of Cook and State of Illinois, have jointly invented certain new and useful Improvements in Yokes for Draft-Gear, of which the following is a specification.

Our invention relates in general to yokes for draft gear and has for its object broadly to provide a yoke which will receive and interlockingly engage with the head of the draw bar of a coupler.

A further object of the invention is to provide a yoke with which the draw bar may be connected by merely inserting the head of the draw bar transversely through the side of the yoke, efficient means being provided to lock the head of the draw bar in place which means may be easily positioned and easily removed.

An additional object of the invention is to provide a yoke for a draft gear, which will be composed of a minimum number of parts so constructed and arranged that when the yoke and draw bar are in operative position upon a railway car the members of the yoke will be held in place by the parts connecting the yoke to the car end holding the yoke in place, obviating thereby the necessity of providing auxiliary fastening means or of permanently securing the draw bar and yoke together and materially reducing the necessary weight and cost of the yoke.

Other objects and advantages of the invention will be apparent, as it is better understood, from the following description when considered in connection with the accompanying drawing illustrating preferred embodiments thereof.

On the drawing:—Figure 1 is a side elevation of a yoke embodying our invention and a portion of a draw bar connected thereto; Fig. 2 is a transverse sectional view taken substantially on the line 2—2 of Fig. 1. Fig. 3 is a perspective view of one form of the removable sliding side wall forming a portion of the yoke; Fig. 4 is a partial perspective view showing a yoke in which are incorporated two removable side walls; Fig. 5 is a transverse section of a somewhat different form of yoke embodying our invention; and Fig. 6 is a partial plan view of the yoke shown in Fig. 5.

Referring to the drawing reference character 11 indicates a draw bar of the type or-

dinarily employed in connection with railway draft gear, reference character 12 designates the body portion of the yoke shown in Figs. 1, 2 and 3, and reference character 13 the slidable side wall or closure for a side of the body of the yoke.

The body portion of the yoke is composed of a pair of parallelly disposed arms 14 terminating at their forward ends in inwardly disposed lugs or shoulders 15 properly shaped to engage behind the head 16 of the draw bar 11. The arms 14 are spaced apart beyond the lugs 15, a distance equal substantially to the height of the head 16 of the draw bar and are connected together at their rear ends as at 17 to give the yoke the customary U-shape form. The entire body portion of the yoke is preferably of rigid inflexible metal.

In Figs. 1, 2 and 3 the yoke is shown as provided with a fixed side wall 18 at one side and a sliding removable wall 19 at the other. The wall 18 is preferably made integral with the arms 14 and extends from the lugs 15 rearwardly coincident with the head 16 of the draw bar. The sliding wall 19 in the embodiment shown in this figure is composed of a flat portion 21 and inwardly extending lips 22 spaced from the main portion 21. In the body portion of the yoke a pair of grooves 23 are provided, one upon each of the outer surfaces of the two arms 14 in which are adapted to seat the lips 22 of this sliding wall. These grooves are closed at their forward ends at 24 to limit the forward movement of the wall. The grooves 23 are spaced inwardly from the adjacent edge of the body portion of the yoke, a distance equal substantially to the distance between the lips 22 and the main body portion 21 of the sliding wall. This arrangement provides a rib 25 between each lip 22 and the main portion 21, which lips prevent lateral movement of the sliding wall with respect to the body portion of the yoke.

In Fig. 4 a yoke is shown which is provided with two sliding walls 19' instead of merely the one shown in Figs. 1 to 3. It is not believed that further description is necessary of this figure, as the walls 19' and the body portion of the yoke are identical with that already described, the groove 23 being duplicated to permit the use of two sliding walls as shown. The yoke shown in Fig. 4 may be made by rolling or forging a strip of thick sheet steel or iron after grooving it

and providing it with the lugs and of course, it may be cast if preferred.

We disclose a modified form of our invention in Figs. 5 and 6, the sliding removable wall 26 being located between the arms 27, which except as immediately hereinafter described are identical with the arms 14 of the earlier embodiment and are connected at one side with a fixed preferably integral wall 28 like the fixed integral wall 18. In this embodiment bosses 29 are formed along the edges of the arms between which the wall 26 is positioned and these bosses and the forward ends of the arms extend outwardly beyond the rear portions of the arms as shown in Fig. 6. In these outwardly extending portions of the arms and in the bosses are provided grooves 32 of appropriate shape to receive the top and bottom edges of the sliding wall 26. In the present instance these edges and the grooves are offset at 33 and are extended inwardly at 34 to form an interlocking connection between the sliding wall 26 and the body portion of the yoke, which will prevent spreading of the arms at this side of the yoke and also outward movement of the sliding wall with respect to the body portion of the yoke as will be readily apparent from viewing Fig. 5.

When either embodiment is employed, the head 13 of the draw bar is inserted sideways between the arms 14 of the body portion of the yoke behind the lugs or shoulders 15 and is moved transversely of the yoke into position. After the head of the draw bar has been positioned in this manner the sliding wall is moved to close the space between the arms and thus retain the head of the draw bar in operative engagement with the yoke. When the earlier embodiment or that shown in Figs. 1 to 4 is employed the sliding plate is slipped over the rear end of the yoke with the lips 22 in engagement with the grooves 23 and is slid forwardly, until these lips engage the closed ends 24 of the grooves. If two sliding walls are used as shown in Fig. 4, one is preferably positioned before the head of the draw bar is inserted between the arms 14. When the embodiment shown in Figs. 5 and 6 is employed the sliding wall 26 is merely inserted between the outwardly extending portions 31 and slid into the position shown in Fig. 6, or until its forward movement is stopped by the closed ends 35 of the grooves 32.

When the draw bar and sliding wall or walls are in position the yoke and draw bar are ready to be operately positioned in the draft gear of the car. When so positioned the sliding wall or walls are prevented from moving rearwardly by the follower plates and springs (not shown) which are ordinarily disposed through the yoke.

It will be apparent that we have provided a yoke for a draft gear, which may be op-

eratively engaged with a draw bar without the use of the rivets, bolts or keys which as is well known to those familiar with the art have been heretofore employed in connection with devices of this character enabling us thereby to provide a yoke for a draft gear composed of a minimum number of parts and of minimum weight. It will be obvious also that these parts are of simple construction and that they may be cheaply manufactured and easily and quickly assembled.

It is thought that the invention and many of its advantages will be understood from the foregoing, without further description and it will be apparent that various changes may be made in the form and construction of the parts without departing from the spirit and scope of the invention or sacrificing any of its material advantages, the preferred embodiments herein before disclosed being merely disclosed being merely preferred embodiments thereof.

We claim:

1. A yoke for a draft gear comprising a body portion provided with longitudinally disposed guide-ways and open at a side to receive the head of a draw bar, and a closure formed to engage said guide-ways and to move longitudinally thereof and adapted to close said open side to retain the head of a draw bar in position.

2. A yoke for a draft gear comprising a body portion provided with longitudinally disposed guide-ways closed at their forward ends, said body portion being open at a side to receive the head of a draw bar, and a closure formed to engage said guide-ways and to move longitudinally thereof and adapted to close said open side to retain the head of a draw bar in position.

3. A yoke for a draft gear comprising a body portion provided with longitudinally disposed guide-ways open at their rear ends, said body portion being open at a side to receive the head of a draw bar, a closure formed to engage said guide-ways and to move longitudinally thereof and adapted to close said open side to retain the head of a draw bar in position, and means for limiting the forward movement of said closure.

4. A yoke for a draft gear comprising a body portion open at a side and having outwardly opening longitudinally disposed guide-ways upon opposite outer sides, and a closure having inwardly extending ribs adapted to engage in said guide-ways and to move longitudinally of said body portion into and out of closing position.

5. A yoke for a draft gear comprising a body portion provided with a longitudinally disposed rib on one face and open at a side to receive the head of a draw bar, a closure for said open side adapted to move longitudinally of said body portion and provided with a recess adapted to embrace said rib

to guide said closure into and out of closing position, and means for retaining said closure in engagement with the opposite face of said yoke.

5 6. A yoke for a draft gear comprising a body portion open at its side to receive the head of a draw bar and provided with a longitudinally disposed recess on one face adjacent said open side, a closure for said open side provided with an extension adapted to

be disposed in said recess and to slide longitudinally thereof to guide said closure into and out of closing position, and means for retaining said closure in engagement with the opposite face of said yoke.
